(57) **CLAIM**

The ornamental design for a camera light, as shown and described.

DESCRIPTION

FIG. 1 is a perspective view, as viewed from the front, of a camera light, showing our new design;

FIG. 2 is a perspective view thereof, as viewed from the rear;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a rear elevational view of a modified embodiment of our camera light;

FIG. 10 is a perspective view thereof, as viewed from the rear; and,

FIG. 11 is a right side elevational view thereof.

The portions shown in dotted line do not form part of the present design.
